Warner R. Buxton, Longmeadow, Mass.

Application June 4, 1935, Serial No. 24,790

8 Claims. (Cl. 150—1.6)

This invention relates to improvements in portfolios.

The invention has for an object to provide in a portfolio, having division walls to form a plurality of pockets, an improved construction which enables one to secure more complete access to the contents of the pockets, for the inspection, selection, removal and insertion of papers, than can be had with the common type of portfolio,—the so-called brief case type,—having pocket provisions.

The invention also has for an object the provision of a portfolio, which when opened, enables the walls thereof to be spread apart and positioned so as to stand substantially upright on a table or desk, with the several pockets fanned out and opened for easy access thereto.

These and other objects will more particularly appear as the detailed description proceeds and will be pointed out in the appended claims.

20 The invention will be disclosed with reference to the accompanying drawings in which:

Fig. 1 is a perspective view of a portfolio, embodying the invention and shown closed;

25 Fig. 2 is a sectional elevational view thereof taken on the line 2—2 of Fig. 1 just inside one of the covers;

Fig. 3 is a fragmentary sectional plan view taken on the line 3—3 of Fig. 1;

30 Fig. 4 is a fragmentary sectional plan view illustrating the reenforcement of the outer end edge of one of the partition members;

Fig. 5 is a top plan view of the portfolio shown in open position; and

35 Fig. 6 is a perspective view of the open portfolio.

Referring to these drawings; the portfolio includes two flat outer walls or covers 10 (Fig. 1) of the same size and shape and made of any suitable flexible material, such as leather or the like.

40 These outer walls 10, which are mounted face to face, are permanently and hingedly connected together along one end edge 11, so that they may be spread apart, swinging about the hinge connection. The necessary hinge connection may be

45 made in any suitable manner. In this case, it is formed by inserting a narrow end wall 12, infolded as best shown in Fig. 3, to form a gusset allowing the walls 10 to move away from one another adjacent the hinge line and provide for the

50 expansion necessary to accommodate the papers carried in the portfolio. This wall 12 (Figs. 1 and 2) extends from the lower side edge 13 of each outer wall upwardly toward, but in this case not quite to the upper side edge 14 and is suitably secured, as by stitches 12', to the walls 10.

As shown, the wall 12 terminates just below one of the two rounded corners 15 which connect the upper side edge 14 to the aforesaid end edge 11 and to the opposite end edge 16.

The two outer walls 10 are interconnected by 5 a plurality of wall members 17 which are constructed of leather, or any other suitable flexible material, and are infolded as best shown in Fig. 6, to form a plurality of pockets 18. The lower side edge of one member 17 is connected to the side 10 edge 13 of one outer wall and the upper edge of said member is connected to the upper edge of the next adjacent member 17. The latter member is connected to the next adjacent member along their meeting lower side edges and so on, 15 adjacent members 17 of the series being connected first along their upper and then along their lower side edges until finally the lower side edge of the last wall 17 of the series is connected to the lower side edge of the other outer wall 10. The 20 various connections described may be made in any suitable manner. As herein shown, the connections are made by stitches 17'.

These wall members 17 cooperate in pairs to form partitions between the outer walls 10. Each 25 two adjacent walls 17 which are interconnected along their upper side edges, constitute one such pair. One or more of such pairs may be used as desired and as shown, two pairs are used, thus affording two double-walled partitions between 30 the covers 10 and providing, in cooperation with the covers, three pockets 18 each open along its upper end. Obviously, other pairs of walls 17 may be added to provide additional pockets, if desired.

The walls 17 are somewhat smaller in area 35 than walls 10 so that the upper side edge and both end edges of each are spaced from the corresponding and adjacent edges of walls 10. These walls 17 may thus lie wholly between and 40 within the margins of walls 10 to be enclosed thereby, when the portfolio is closed. Walls 17 are not secured to walls 10 except along the edges described. Both end edges and, more especially the outer end edge of each wall 17, is 45 free of connections with walls 10. This allows the walls 17 to be spread apart as walls 10 are swung open on their hinge connection, to put the portfolio in the self sustaining position shown in Fig. 6. To assist in making the walls 17 stand 50 more or less upright, as shown in Fig. 6, these walls are suitably reenforced. While the necessary reenforcement may be provided in any suitable way, I have found the expedient shown in Figs. 2 and 4 a simple, inexpensive and satisfac- 55

tory solution of the problem. A wire 19 is applied along the outer end edge of each wall 17 and held in place by folding over it the margin of the outer wall, as shown in Fig. 4. The several 5 wires 19 are not interconnected and therefore do not interfere with relative movement of the walls 17. Each wire acts independently of the other to hold its wall against collapse or bending while standing on its lower edge in a more or less upper 10 right position.

The walls 17 need not be connected together except along the side edges described. Still, it is possible to secure them together to a limited extent along their end edges as illustrated in Fig. 2 15 where the stitches 17' extend part way along this end edge. To do so helps to some extent in stiffening up the walls to make them self-sustaining when placed as shown in Fig. 6.

According to the broader features of the invention, the walls 10 may be held against substantial movement on their hinge connection, and in position to enclose the walls 17, in any suitable way. A satisfactory and convenient way is that illustrated, wherein separable fastener means of 25 the so-called zipper type are used. A tape 20 carrying a series of fastener fingers 21, is fastened to each wall 10 and extends along the end edge 16, around one corner 15 and along the side edge 14 to and around the other corner, terminating just above the top of end wall 12. The usual slide, shown at 22, serves to cause the two sets of fingers 21 to engage or disengage. When this slide 22 is positioned as shown in Figs. 2, 5 and 6, all the fingers 21 are disengaged. The 30 slide, when moved from such position to its other extreme position (at the intersection of edges 13 and 16) will cause all the fingers 21 to be engaged, whereby walls 10 are then held together along all edges except the lower side edge. However, one cannot gain access to the contents of 40 the portfolio from the bottom or lower side edge thereof. All that is possible is to reach into the empty spaces between pairs of the walls 17 as will be clear from Fig. 6.

45 The invention provides a novel form of partitioning means for portfolios. The pockets, provided by such means, are characterized by their accessibility. The partitioning means are characterized by their function of supporting the portfolio in upright position with the pockets spread open for the easy selection of papers from the several pockets or for the filing of papers in such pockets. A pull on the zipper slide 22 into the position shown in Fig. 2, releases walls 10 from 50 their interconnections, except along their adjacent and hinged end edges 11. Then, if the portfolio is held upright with its lower edge resting on a desk or table, the walls 10 may be swung apart, about the axis of their hinge connection, 55 into a self-sustaining position. In spreading the walls 10 apart, the walls 17 are likewise spread and the pockets 18 are opened to facilitate inspection, selection and removal of papers and also to enable convenient filing of the same. And 60 these walls 17, reinforced as described, become, when spread apart, capable of standing upright. Each wall 17 of one pair braces the other wall of the pair and forms a sufficient support for the portfolio independently of the outer walls 10. 65 These walls 10, as shown, bend along a substantially diagonal line extending from the intersection of edges 13 and 16 to the upper end of end wall 12 near the zipper slide. One half of each wall 10 thus lops over and bends down until the edges 14 and 16 rest in whole or in part 70

on the table or desk. Naturally these walls 10 could readily be made so as not to bend down in the manner described but this action is considered an advantage in that it enables easier and more complete access to the papers in the two outer pockets. When the portfolio is to be closed, the bent down corners of walls 10 are lifted and the walls swung together as much as possible, thus moving the pocket-forming walls together. The portfolio is then closed by pulling the zipper slide into its other extreme position, above described. 10

The invention thus affords a portfolio of improved construction, which provides for partitioning into pockets and yet, when opened, allows 15 much better access to the contents and enables the desired papers to be located, removed and replaced more easily and conveniently than is possible in the conventional type of brief case usually employed and having pockets. 20

What I claim is:

1. A portfolio, comprising, a pair of outer walls hingedly connected together along one end edge, a plurality of wall members interconnecting one side edge of one outer wall to the corresponding side edge of the other outer wall and infolded to lie between the outer walls and partition the space therebetween thereby forming a plurality of pockets open adjacent the opposite end and side edges of said outer walls, and separable fastener means for holding said outer walls together and preventing relative swinging movement thereof about the hinge connection therebetween. 25

2. A portfolio, comprising, a pair of outer walls hingedly connected together along one end edge, 30 a plurality of wall members interconnecting one side edge of one outer wall to the corresponding side edge of the other outer wall and infolded to lie between the outer walls and partition the space therebetween thereby forming a plurality of pockets open adjacent the opposite end and side edges of said outer walls, said outer walls being larger in area than the infolded members and extending beyond both end edges and one side edge thereof, a row of fasteners along the other end edge and second named side edge of each outer wall, and means slidabie in one direction to engage and in the opposite direction to disengage said rows of fasteners to hold the outer walls together in closure forming relation with 40 the open ends of said pockets. 45

3. A portfolio, comprising, companion outer walls, a plurality of wall members interconnecting one side edge of one outer wall to the corresponding side edge of the other outer wall and infolded to lie between the outer walls and partition the space therebetween thereby forming a plurality of pockets each open at opposite ends and adjacent the other side edges of said outer walls, said infolded wall members being otherwise free of connections to the outer walls, said outer walls being larger than the infolded members and projecting beyond opposite ends of each thereof and beyond that side which lies adjacent the open end of the pocket, said outer walls being 55 hingedly connected along one end edge, whereby they may be swung apart to spread the infolded wall members and open wide the pockets, and separable fastener means for interconnecting the outer walls to hold them against swinging movement. 60

4. A portfolio, comprising, companion outer walls, a plurality of wall members interconnecting one side edge of one outer wall to the corresponding side edge of the other outer wall and 75

infolded to lie between the outer walls and partition the space therebetween thereby forming a plurality of pockets each open at opposite ends and adjacent the other side edges of said outer walls, said infolded wall members being otherwise free of connections to the outer walls, said outer walls being larger than the infolded members and projecting beyond opposite ends of each thereof and beyond that side which lies adjacent the open end of the pocket, said outer walls being hingedly connected along one end edge, whereby they may be swung apart to spread the infolded wall members and open wide the pockets, and separable fastener means for interconnecting the outer walls along their second-named side edges and other end edges to prevent swinging movement of the outer walls and escape of contents from said pockets.

5. A portfolio, comprising, two outer walls hingedly connected along one end edge, rows of separable fasteners one row for each wall and each row arranged along the opposite end edge and one side edge of its wall leaving the other side edge free, a member movable in one direction to engage and in the opposite direction to disengage said rows of fasteners, a series of partition walls intervening between the outer walls and adapted to be enclosed between the outer walls when said rows of fasteners are engaged, successive partition walls of the series being connected first along one side edge and then along the opposite side edge and the end walls of the series being connected one to each outer wall along the free side edge thereof.

20 6. A portfolio, comprising, two outer walls hingedly connected along one end edge, rows of separable fasteners one row for each wall and each row arranged along the opposite end edge and one side edge of its wall leaving the other side edge free, a member movable in one direction to engage and in the opposite direction to disengage said rows of fasteners, a series of partition walls intervening between the outer walls and adapted to be enclosed between the outer walls when said rows of fasteners are engaged,

successive partition walls of the series being connected first along one side edge and then along the opposite side edge and the end walls of the series being connected one to each outer wall along the free side edge thereof, said partition walls being otherwise free of connections to the outer walls and free to float therebetween.

7. A portfolio, comprising, a pair of covers hingedly connected along one edge, separable fastener means for holding the covers together along the other end edge and one side edge of each, said covers when said fastener means are released adapted to be spread apart swinging on said hinge connection and supported from the other side edge of each with at least a substantial portion of each cover in substantially upright position, and at least one pair of wall members intervening between the covers, the members of each pair having their upper side edges connected together and their lower side edges connected one to the lower side edge of each cover to be spread apart into inverted V-form thereby forming a braced support for holding the portfolio while open in upright position.

8. A portfolio, comprising, a pair of covers hingedly connected along one edge, separable fastener means for holding the covers together along the other end edge and one side edge of each, said covers when said fastener means are released adapted to be spread apart swinging on said hinge connection and supported from the other side edge of each with at least a substantial portion of each cover in substantially upright position, and at least one pair of wall members intervening between the covers, the members of each pair having their upper side edges connected together and their lower side edges connected one to the lower side edge of each cover to be spread apart into inverted V-form thereby forming a braced support for holding the portfolio while open in upright position.

WARNER R. BUXTON. 45
